UNITED STATES PATENT OFFICE.

AURELE VERMEULEN, OF LOS ANGELES, CALIFORNIA.

NONREFILLABLE CONTAINER.

1,427,245.

Specification of Letters Patent. Patented Aug. 29, 1922.

Application filed October 13, 1920. Serial No. 416,639.

To all whom it may concern:

Be it known that I, AURELE VERMEULEN, a citizen of the United States, residing at Los Angeles, in the county of Los Angeles and 5 State of California, have invented new and useful Improvements in Nonrefillable Containers, of which the following is a specification.

This invention relates to means whereby a 10 container when once capped cannot be refilled without showing marks of refilling. The invention has for an object the provision of means for preventing the refilling of containers or receptacles. Another object is the provision of a device of this character which will protect the contents of a 15 receptacle, which will guarantee the genuineness of the contents in the receptacle and which will prevent the closure member, such 20 as a cork, lid or cover, from being accidentally removed and the contents lost.

In practising the invention, I provide means which is permanently imbedded in or 25 fixedly joined in some manner to the receptacle. Said means in one embodiment may comprise a metallic strip or wire. Preferably two strips or wires are provided and imbedded or fixedly joined to the receptacle on diametrically opposed sides thereof. 30 When the cover, cork or lid is placed upon the receptacle, after said receptacle has been filled, the wires are brought upwardly and over said closure and twisted or otherwise 35 permanently united, so as to seal the closure against release unless one of said wires is first severed. It is therefore obvious that if a buyer should purchase a bottle and the sealing device was broken, there would be 40 presumptive evidence that the contents might have been tampered with, and the buyer would be fully justified in demanding a bottle in which the sealing means was intact.

It is obvious that a device of this character is simple and inexpensive, and does 45 not require particular apparatus for a carrying of the same into effect. It is a positive guaranty against a tampering of the contents within the container or receptacle.

50 The invention has for further objects the provision of an improved sealing device for receptacles which will be superior in point of relative simplicity and inexpensiveness, taken in conjunction with utility, durability, 55 and general efficiency and serviceability.

With the above and other objects in view,

the invention consists in the novel and useful provision, formation, construction, combination, association and inter-relation of parts, members and features, all as disclosed 60 in the accompanying drawing, described in the following statement, and finally pointed out in claims.

In the drawing:

Figure 1 is a fragmentary cross-sectional 65 view of a container utilizing the improved sealing device, with said sealing device ready for use;

Figure 2 is a view similar to Figure 1, showing a closure means applied to the receptacle, and the improved sealing device 70 passed over said closure means and permanently united so as to seal the closure;

Figure 3 is a top plan view showing the sealing device passed over the closure member 75 of a container with the sealing device partially twisted;

Figure 4 is a view similar to Figure 3 with the exception that the sealing device has been flattened or heated sufficiently to 80 cause the sealing device to become welded;

Figure 5 show the sealing device broken or severed;

Figure 6 is a fragmentary perspective 85 view of the sealing device applied over the closure of said container; and

Figure 7 shows the sealing device severed.

Corresponding parts in all the figures are designated by the same reference characters. 90

Referring with particularity to the drawing, which illustrates one embodiment of the invention, A designates a container and B a sealing device adapted to extend over a closure member C applied to said container, 95 in such relation that the sealing device B must have one of its members severed in order to release the closure C.

In the drawing the container A is shown in the form of a bottle having the usual 100 neck, 1, provided with a rim 2. When the container A is first made, in the case of a bottle, the sealing device B, which may include metallic members 3 and 4, have one of their ends, as 5 and 6, permanently embedded 105 in the rim portion 2 of the container A. The metallic members 3 and 4 preferably have their ends curled, as shown at 7 and 8, so that it would be difficult in any manner to pull the members 3 and 4 from the rim portion 2 of the container A. Obviously, to 110 merely insert a metallic member within the

rim portion 2 without in some manner twisting the end would allow the metallic member to be easily removed and a new metallic member inserted with some adhesive substance.

As shown in Figure 1, the sealing means B may comprise but two members as 3 and 4 permanently embedded at some portion in the container. Where two members are used, as shown, it is preferable to locate them on diametrically opposite sides of the container and adjacent the opening in said container. Obviously, it would be an easy matter to provide the container with a plurality of such sealing means, each one of which was held at a plurality of points in the container.

Referring to Figure 2, it will be observed that the container A has been filled with some substance such as liquid 9, and that a closure member such as a cork 10 has been inserted in the opening of the container A. In Figure 3 the sealing device B which, as stated, may comprise metallic members 3 and 4, are brought upwardly and allowed to extend over the cork 10 whereupon the ends as 11 and 12 are given a half twist. In Figure 4 the head portion 13 where the ends as 11 and 12 were twisted, has been flattened or heated sufficiently so as to weld a joint at the head portion 13 of the ends 11 and 12 of the sealing device B. Obviously, the ends 11 and 12, instead of being welded together, might have a drop of solder placed thereon, however, the solder might be burned off and this would defeat the very objects of the means as stated in the first part of this specification. Some device might be placed over the ends such as a ring member, but a person tampering with the bottle and desiring to remove the contents might be able to remove the ring so that the cork might be lifted a sufficient distance to allow the contents to be contaminated or removed, or new contents placed within the container A. The inventor has therefore deemed it most expedient that the sealing device itself have its ends flattened or welded together as shown in Figure 4 so that any tampering can be readily noticeable and the only way by which access to the contents within the container A may be gained is clipping the sealing device as shown in Figure 5.

It is obvious that a device of this character is simple, and that it is possible for a manufacturer to guarantee the genuineness of the contents in a receptacle. The sealing device may be made of metal or might be made of textile material, wood or rubber, so that a deformation of the sealing device would easily lead to discovery that the contents within the container had been tampered with.

The sealing device B might be of some

material that would break easily; that is to say, if the sealing device was brought up and over the closure member and given a half twist, as shown in Figure 3, a releasing from said twist would tend to separate one of the parts from the other and make a re-joining of the parts impossible, for if it were attempted to again twist them into the shape shown in Figure 3, one of the members or both of them would give way.

It is obvious that many changes and variations and modifications may be made in departure from the particular description and showing of the accompanying drawing in adapting the invention to varying conditions and requirements of use and service, without departing from the true spirit of the invention.

I claim:

1. A container formed with an enlargement surrounding the orifice portion thereof; there being means adapted to close the orifice of said container; a sealing device having a portion thereof embedded in said enlargement and projecting from the under surface of said enlargement and over the means adapted to close the orifice.

2. A container formed with an enlargement surrounding the orifice portion thereof; there being means adapted to close the orifice of said container; a sealing device having a portion thereof embedded in said enlargement and projecting from the under surface of said enlargement and over the means adapted to close the orifice; said sealing device comprising members adapted to be inter-engaged in sealing relation.

3. A container formed with an enlargement surrounding the orifice portion thereof; there being means adapted to close the orifice of said container; a sealing device having a portion thereof embedded in said enlargement and projecting from the under surface of said enlargement and over the means adapted to close the orifice; the embedded portion of said sealing device being provided with curled ends to prevent an easy removal of said sealing device.

4. As an article of manufacture, a bottle including the usual neck portion, there being means adapted to be received within the neck for closing the bottle; a sealing device having a portion thereof embedded in the neck and projecting transversely outwardly from the periphery thereof; said means being adapted to pass over the means for closing the bottle.

In testimony whereof, I have signed my name to this specification in the presence of two subscribing witnesses:

AURELE VERMEULEN.
